UNITED STATES PATENT OFFICE.

WALTER O. PEALE, OF PITTSBURGH, PENNSYLVANIA, ASSIGNOR TO WESTINGHOUSE ELECTRIC AND MANUFACTURING COMPANY, A CORPORATION OF PENNSYLVANIA.

ELECTRIC HEATER.

1,075,436.

Specification of Letters Patent.

Patented Oct. 14, 1913.

Application filed March 13, 1911. Serial No. 614,235.

To all whom it may concern:

Be it known that I, WALTER O. PEALE, a citizen of the United States, and a resident of Pittsburgh, in the county of Allegheny and State of Pennsylvania, have invented a new and useful Improvement in Electric Heaters, of which the following is a specification.

My invention relates to electric heaters, 10 and it has special reference to such air heaters as are employed in the manufacture of candy and are commonly known as "batch heaters".

The object of my invention is to provide 15 a device of the above-indicated character which shall be simple, inexpensive and durable in construction, efficient in operation and particularly adapted to effectively direct and concentrate the heat generated in 20 its several heater units at a particular distance in front of the heater.

Heretofore, electric air heaters have been constructed which embodied a plurality of heater units arranged vertically side-by-side 25 and a single heat reflector. With such an arrangement, it is evident that the several heater units were affected by the heat of the adjacent units in approximately the same degree, so that all of the units operated under 30 substantially the same conditions and could, therefore, be designed and constructed alike.

According to my present invention, I provide an electric heater in which the several heater units are horizontally disposed and 35 arranged one above another, each unit being provided with an individual heat reflector which projects between the adjacent units in such manner as to prevent the heat from the lower units from rising and causing the 40 upper units to be operated at excessive temperatures. With this arrangement, each heater unit is operated independently and under the same heat conditions, so that all the units may be constructed alike and are 45 interchangeable.

In the accompanying drawing, Figure 1 is 50 a front elevation of a device constructed in accordance with my invention, a portion of one of the heater units being removed to show the construction thereof. Fig. 2 is a 55 sectional view on a line II-II of Fig. 1, Fig. 3 is a similar view on the line III-III of Fig. 1, and Fig. 4 is a similar view on the line IV-IV of Fig. 1.

Referring to the drawing in detail, the

device here shown comprises a plurality of heater units 1 and 2, a plurality of supporting brackets 3, 4 and 5, heat reflecting plates 6 and 7, and end plates 8 and 9.

The heater units 1 and 2 are of like construction and preferably comprise resistance elements 10 which are slotted on alternate sides to provide a zig-zag path for the current and which are assembled between suitable insulating members 11 and 12 and incased in a metal sheath 13.

The particular structure of heater units 1 and 2 forms no part of my invention and hence any of the well known types of heater units may be employed. These heater units 70 1 and 2 are horizontally disposed and arranged one above the other, being secured to the supporting brackets 3, 4 and 5 in a suitable manner. The end supporting brackets 3 and 5 are provided with supporting plates 75 14 having insulating bushings 15 to receive the conductor leads 16, said leads being electrically connected to the resistance elements 10 in a well known manner.

The method of connecting the several 80 heater units pertains in no way to my invention and those skilled in the art will readily understand that they may be connected in series, in parallel or in any other desired relation.

The reflecting plate 6 constitutes the back portion of the heater and extends upwardly and forwardly in order to reflect the heat of the upper heater unit 1 to a point at any desired distance in front thereof. The upper 90 portion of the plate 6 is suitably secured to the supporting brackets 3, 4 and 5 and to the end plates 8 and 9 which form the sides of the device. Plate 7 also extends upwardly and is curved forwardly in such manner as 95 to project between the heater units 1 and 2 and to prevent the heat generated by the unit 2 from materially affecting the operation or the temperature of the upper unit 1. The curvature of the reflector plates 6 and 100 7 depends entirely upon the distance in front of the heater that it is desired to concentrate the heat.

Bushings 17 are provided in the reflecting plates 7 to protect the conductor leads 16, 105 and plate 7 is suitably secured to the end plates 8 and 9 in order to form a rigid structure.

I have shown and described a heating device embodying horizontally disposed heater 110

units arranged one above the other, but it is evident that my invention is applicable to devices in which the heater units are arranged vertically side by side. Other modifications in the arrangement and location of parts may be effected without exceeding the scope of my invention, and I desire that only such limitations shall be imposed as are indicated in the appended claims.

10 1. I claim as my invention:

1. An electric heater comprising a plurality of heater units disposed one above another, and a heat reflector for each unit disposed one above another.

15 2. An electric heater comprising a plurality of horizontally disposed heater units located one above another, and a plurality of heat reflectors therefor.

3. In an electric heater, the combination 20 with a plurality of parallel heater units, of a heat-reflecting wall between the units of each pair.

4. In an electric heater, the combination 25 with a plurality of horizontally disposed heater units arranged one above another, of

a heat-reflecter for each unit adapted to prevent the heat thereof from influencing the above adjacent unit.

5. An electric heater comprising a plurality of horizontally disposed heater units 30 arranged one above another, a curved back plate extending upwardly and forwardly over the uppermost heater unit to form a reflector therefor, a similar plate extending upwardly and forwardly over the adjacent 35 lower heater unit, and suitable end plates to which said curved plates are attached.

6. An electric heater comprising a plurality of horizontally disposed heater units arranged one above another, of means for 40 preventing the heat generated by the lower heater units from influencing the temperature of the upper heater units.

In testimony whereof, I have hereunto subscribed my name this 6th day of March 45 1911.

WALTER O. PEALE.
